CLAIM

The ornamental design for a charging cradle, as shown and described.

DESCRIPTION

FIG. 1 is a perspective view of a charging cradle showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a first element of the charging cradle thereof;

FIG. 9 is a perspective view of a second element of the charging cradle thereof; and,

FIG. 10 is a perspective view of a third element of the charging cradle thereof.

The broken lines shown in the drawings depict portions of the charging cradle in which the design is embodied that form no part of the claimed design.
